UNITED STATES PATENT OFFICE

2,576,654

CATTLE RESTRAINING APPARATUS

Alvin E. Thorson, Victor, Mont.

Application June 1, 1949; Serial No. 96,475

3 Claims. (Cl. 119—99)

1

This invention relates to new and useful improvements and structural refinements in restraining apparatus for cattle, and the principal object of the invention is to securely hold cows and other animals while they are being branded, dehorned or otherwise operated upon, so that the operation may be performed with speed, convenience and efficiency, and without interference from movement of the animal.

Some of the important features of the invention involve the provision of different means for restraining the animal against possible movement, while at the same time permitting convenient access to different portions of the animal's body where the necessary operation is to be performed.

Some of the advantages of the invention reside in its simplicity of construction, in its convenient and expeditious operation, and in its adaptability to economical manufacture.

With the above more important objects and features in view and such other objects and features as may become apparent as this specification proceeds, the invention consists essentially in the construction and arrangement of parts as shown in the accompanying drawings, in which:

Figure 1 is a perspective view of the invention;

Figure 2 is a side elevational view thereof;

Figure 3 is a cross-sectional view, taken substantially in the plane of the line 3—3 in Figure 2;

Figure 4 is an end view, taken in the plane of the line 4—4 in Figure 2;

Figure 5 is a fragmentary perspective view on an enlarged scale, illustrating the locking means for one of the side bars used in the invention;

Figure 6 is an end view, taken in the plane of the line 6—6 in Figure 2; and

Figure 7 is a group perspective view on an enlarged scale, illustrating the suspension of the entrance closure or door used in the invention.

Like characters of reference are employed to designate like parts in the specification and throughout the several views.

Referring now to the accompanying drawings in detail, the invention consists of a cattle-restraining apparatus designated generally by the reference character 10, the same embodying in its construction a box-shaped frame 12 consisting of a pair of spaced parallel base members 14 connected together by a pair of longitudinal members 16 which, in turn, carry a base plate 18, as is best shown in Figure 3.

2

The frame 12 also includes a set of corner posts 20, 22, the former being somewhat shorter than the latter substantially as shown. The corner posts 20 are disposed at one end of the apparatus 10, while the posts 22 are disposed at the relatively opposite end, and a pair of longitudinal top members 24 connect together the upper portion of the posts 20, 22 while the posts 20 themselves are connected together at their upper ends by a transverse top member 26. Similarly, the upper end portions of the corner posts 22 are connected together by vertically spaced transverse members 28, 30, as is best shown in Figure 1.

A pair of spaced side walls 32, 34 are mounted within the frame 12 and, being adapted to receive an animal therebetween, define what may be referred to as an animal-receiving or restraining chamber 36, having an entrance end 38 and an exit end 40. (See Figure 1.)

With minor exceptions, the side walls 32, 34 are similar in construction, so that a description of one will, to a large extent, suffice for both.

Each of the side walls 32, 34 is substantially rectangular and consists of a horizontally elongated bottom panel 42 provided with a pair of side members or end members 44 which extend upwardly and are connected together at their upper ends by a top member 46.

A horizontal rod 48 extends between the end members 44 in adjacent parallel relation to the upper edge of the bottom panel 42, and a plurality of upwardly extending side bars 50 are provided at their bottom ends with transverse, tubular portions or sleeves 52 which are rotatably mounted in longitudinally aligned relation on the rod 48 so that the bars 50 may be individually swung outwardly from the side wall as indicated by the arrow 54 in Figure 1.

It should be understood that when the invention is placed in use, an animal is clamped in the chamber 36 by the side walls 32, 34, and the above described facilities for individually swinging the side bars 50 outwardly provide means for gaining convenient access to different portions of the animal's body.

Means are provided for locking the side bars 50 in position, these means consisting of a set of U-shaped brackets 56 secured to the top members 46 of the side walls (see Figure 5) and equipped with pivotally mounted wire keepers 58 which are engageable with upper end portions of the bars 50 so as to releasably retain the bars 50 in proper position. Needless to say, individual

locking means of this type are provided for each side bar, so that other bars need not be disturbed if only one particular bar is to be swung outwardly.

If desired, the bottom panel or member 42 of the side wall 32 may be provided with a door opening equipped with a removable door 60, so that access may be had to lower portions of the animal's body. The door 60 is simply retained in its position by a pair of bolts or latches 62 slideable in relatively opposite directions by the actuation of a suitable lever 64 pivoted to the door, the latches 62 being engageable with suitable brackets or sockets 66 mounted on the side wall 32. If desired, the door 60 may be removed from the side wall, or it may be merely opened, the latter arrangement being facilitated by a hinge pin 68 whereby the door may be swingably attached to the associated side wall.

The mounting of the side walls 32, 34 in the frame 12 will now be explained, the side wall 32 being pivotally or hingedly connected at the lower edge of its bottom member 42 to the base plate 18 of the frame, as indicated at 70, while the side wall 34 is swingable, as well as slideable, toward and away from the side wall 32. This is achieved by extending the end members 44 of the side wall 34 downwardly through suitable slots 72 provided in the base plate 18 as shown in Figure 3, these downward extensions of the side wall end members being indicated at 74 and being connected by suitable tension springs 76 to one of the longitudinal base members 16. Moreover, lengths of chain 78 are connected to the extension 74 and are lockably engageable with keyhole slots 80 provided in the remaining base member 16, so that while the springs 76 tend to draw the side wall 34 away from the side wall 32, the distance of the lower edge of the side wall 34 from the lower edge of the side wall 32 may be preadjusted by simply engaging different links of the chain 78 with the slots 80, as will be clearly apparent.

However, it is to be noted that the attachment of the springs 76 and chains 78 to the extension 74 facilitates swinging movement of the side wall 34 toward and away from the wall 32, while similar movement of the wall 32 with respect to the wall 34 is, of course, facilitated by the hinge or pivot connection 70. Accordingly, the two side walls may be swung or drawn together so as to clamp an animal therebetween or, alternatively, may be swung apart so as to release the animal. Moreover, the adjustment facilitated by the slideable positioning of the extensions 74 in the slots 72 enables the distance between the lower edges of the two side walls to be increased or decreased so as to effectively accommodate animals of different sizes.

The swinging of the side walls 32, 34 is effected by means of a lever 82 which is secured to a longitudinal shaft 84 journaled in the aforementioned members 26, 28 and provided with a pair of bellcranks 86 which, in turn, are operatively connected by suitable links 88 to upper edges of the side walls 32, 34. The outer end portion of the lever 82 is provided with a drop cord 90, and it will be apparent from the foregoing that by pulling this cord downwardly, the walls 32, 34 will be drawn together so as to clamp an animal in the chamber 36. Means are provided for locking the side walls against outward swinging movement, these means consisting of a toothed segment 92 secured to a cross member 94 carried by the aforementioned top members 24, the lever

82 being provided with a pawl 96 which is urged by a tension spring 98 in engagement with the segment 92 (see Figure 1) so as to lock the lever 82 and the side walls 32, 34 against outward swinging movement, as aforesaid. However, the pawl 96 is also provided with a drop cord 100, so that by simply pulling this cord downwardly the pawl may be disengaged from the segment 92 to release the lever 82 and to facilitate spreading of the side walls 32, 34.

The entrance end 38 of the animal restraining chamber 36 is equipped with a slideable door or closure 102 provided at the upper edge thereof with a bracket 104 carrying a carriage 106 and with additional brackets 108 carrying a tubular slide 110.

The carriage 106 and the slide 110 are movable longitudinally in a tubular guide 112 secured to the frame 12 by suitable brackets 114, the guide 112 being provided in the bottom thereof with a longitudinally extending slot 116 through which the brackets 104, 108 may extend into the guide. (See Figure 7.)

The closure or door 102 is equipped with a suitable handle 118 so that sliding thereof may be effected, and the bottom portion of the door is guided by suitable fingers 120, 122 which slideably engage a guide rod 124 secured to one of the base members 14.

The exit end 40 of the animal-restraining chamber 36 is also provided with a closure or door 126 which is hingedly attached as at 128 to one of the corner posts 22 and is equipped with a spring-pressed latch or bolt 130 so that it may be retained in a closed position. This latch, which is engageable with a bracket or socket 132 mounted on another of the corner posts 22, is actuated by a depressible foot pedal 134, the latter being pivoted to the door 126 and being so arranged that by simply depressing the pedal 134 the latch 130 is released from the socket 132 to facilitate opening of the door.

A downwardly inclined head rest 136 is secured to the outer surface of the door 126 and the upper edge portion of the door is recessed, as at 138, so as to receive the neck of the animal, as shown at 140 in Figure 6.

Means are provided for preventing the animal from moving its head, these means consisting of a restraining member 142 which is vertically slidably in a pair of guides 144 provided on the corner posts 22 at the exit end of the apparatus, the bottom edge of the member 142 being provided with a wire rod 146 which has an arched intermediate portion 148 adapted to engage the neck of the animal. The restraining member 142, together with the rod 146 are slid upwardly and downwardly by the actuation of a lever 150 which is pivoted to a bracket 152 mounted on the frame 12 and is operatively connected by a link or rod 154 to the member 142, as is best shown in Figure 1.

The lever 150 is also provided with a drop cord 156 whereby the member 142 may be slid downwardly toward the door 126, but a tension spring 158 is connected to the lever 150 and is also connected, as at 160, to one of the base members 14, whereby the restraining member 142 is normally urged upwardly from the door 126, as will be clearly understood.

Means are provided for locking the restraining member 142 against upward sliding movement, these means consisting of a vertical rod or shaft 162 which is secured to the member 142 and is provided with a plurality of notches 164 engage-

able by a locking arm 166 through which the shaft 162 slides. This arm is mounted by means of a spring-loaded bolt 168 on the frame member 30 and is provided with a drop cord 170, so that by simply pulling this drop cord downwardly, the arm 166 may be released from the notches 164 in the shaft 162 and the restraining member 142 may be permitted to slide upwardly by the resiliency of the spring 158.

Finally, the invention contemplates the provision of means engageable with the nose of the animal for restraining the animal's head against movement about the axis of the neck, these last-mentioned means involving the provision of a rod 172 which has one end portion thereof selectively receivable in a plurality of apertures 174 provided in a bracket 176 attached to the door 126, this rod having an arched intermediate portion 178 engageable with the nose of the animal while the head of the animal is supported by the rest 136.

The remaining end portion of the rod 172 is removably retained in position by a notched keeper bar 180 which is removably and adjustably positioned in a guide rod 182 secured to one of the corner posts 22 while the notches thereof are selectively engageable with a keeper pin 184 with which the guide rod 182 is provided, as is best shown in Figures 1 and 6. The keeper bar 180 is equipped at one end thereof with a hook-shaped extremity 186 adapted to engage the restraining rod 172, whereby the latter will be firmly yet adjustably retained in position to clamp the animal's nose. However, it is to be noted that the keeper bar 180 may be removed from the guide rod 182 and from the restraining rod 172 so as to facilitate opening and closing of the door 126.

It is believed that the advantages and use of the invention will be clearly apparent from the foregoing disclosure, and accordingly, further description thereof at this point is deemed unnecessary.

Having described the invention, what is claimed as new is:

1. In a cattle restraining apparatus, the combination of a base, a pair of spaced side walls provided on said base and adapted to receive an animal therebetween, one of said side walls being pivoted at its lower edge to said base, the second side wall having its lower edge pivotally and slidably attached to the base whereby said walls may be swung toward and away from each other and whereby the distance between the lower edges thereof may be varied, common means for swinging said walls, means for locking said walls against outward swinging movement, additional means for sliding the lower edge portion of said second wall toward and away from the first wall, a head rest provided for cooperation with a closure at one end of the apparatus, means engageable with the neck of an animal in said chamber for retaining the head thereof on said rest, said last-named means including a restraining member vertically reciprocable in a pair of guides adjacent the exit closure of the chamber, a wire rod having an arched intermediate portion engageable with the neck of an animal and

provided on said restraining member, means for locking the restraining member against upward movement including a vertical rod attached to the restraining member, a plurality of notches on said rod, a lock arm engageable with said notches and said arm being mounted by means of a releasable spring-loaded bolt.

2. In a cattle restraining apparatus, the combination of a base, a pair of spaced side walls 10 mounted on said base for movement toward and away from each other and defining an animal receiving chamber therebetween, said chamber having entrance and exit closures provided at the respective ends of said chamber, a head rest 15 provided on the exit closure, means engageable with the neck of an animal in said chamber for retaining the head thereof on said rest, said last-named means including a restraining member vertically reciprocable in a pair of guides 20 adjacent the exit closure, a wire rod having an arched intermediate portion engageable with the neck of an animal, said rod being provided on said restraining member, means for locking the restraining member against upward movement 25 including a vertical rod attached to the restraining member, a plurality of notches on said rod, a lock arm engageable with a preselected one of said notches, said arm being mounted by means of a releasable spring loaded bolt.

3. In a cattle restraining apparatus, the combination of a base, a pair of spaced side walls mounted on said base for movement toward and away from each other and defining an animal receiving chamber therebetween, said chamber 30 having entrance and exit closures provided at the respective ends of said chamber, a head rest provided on the exit closure, means engageable with the neck of an animal in said chamber for retaining the head thereof on said rest, said last- 35 named means including a restraining member vertically reciprocable in a pair of guides adjacent the exit closure, a wire rod having an arched intermediate portion engageable with the neck of an animal, said rod being provided on 40 said restraining member, means for locking the restraining member against upward movement including a vertical rod attached to the restraining member, a plurality of notches on said rod, a lock arm engageable with a preselected one of 45 said notches, said arm being mounted by means of a releasable spring loaded bolt, nose-restraining means provided on said exit closure for co- 50 action with said head rest, and a resilient means for urging said restraining member to an upper 55 position.

ALVIN E. THORSON.
